UNITED STATES PATENT OFFICE.

CLARENCE A. BURTON, OF KANSAS CITY, KANSAS, ASSIGNOR OF TWO-THIRDS TO LOREN G. ROWELL, OF SAME PLACE, AND ALEXANDER R. KLEBBA, OF ST. LOUIS, MISSOURI.

JOURNAL-BEARING.

SPECIFICATION forming part of Letters Patent No. 487,236, dated November 29, 1892.

Application filed February 3, 1892. Serial No. 420,209. (No model.)

To all whom it may concern:

Be it known that I, CLARENCE A. BURTON, of Kansas City, in the county of Wyandotte and State of Kansas, have invented certain new and useful Improvements in Journal-Bearings, of which the following is a full, clear, and exact description, reference being had to the accompanying drawings, which form a part of this specification.

10 My invention relates to certain new and useful improvements in axle or other bearings intended more especially for railways; and my invention consists in certain features of novelty hereinafter described, and pointed out in the claims.

Figure I represents a side elevation of my improved device as applied to railway-trucks. Fig. II is an enlarged vertical section of the same. Fig. III is a vertical section taken on line III III, Fig. I. Fig. IV is a detail perspective view showing the outer plate of the boxing. Fig. V is a detail sectional view showing the detached lower portion of the boxing. Fig. VI is a sectional view showing 25 a modification of the lower detached portion of the boxing.

Referring to the drawings, 1 represents a rail, showing wheels 2 of a car-truck resting thereon.

30 3 represents the truck-frame, to which is secured supporting-bars 4, said bars being secured to the journal-boxes 5, as shown at 6.

7 represents a tie-bar secured to the lower ends of the journal-boxes, as shown at 8, in order to brace the same and keep them in a vertical position.

9 represents a tie-bar secured to the tops of the journal-boxes, as shown at 10, also to brace the same.

40 11 represents the main portion of the journal-box, to which is secured a section 12 by means of bolts 13, passing through flanges 14 on the respective portions of said box.

15 represents an axle on which rests two 45 rollers 16, having a shaft 17, on which rests a roller 18, having a shaft 19.

20 represents blocks, preferably of cast-iron, having their lower ends resting on the two ends of the shaft 19, as shown at 21, said

blocks supporting the journal-box 11 by having the same resting thereon, as shown at 22, said blocks being provided with oil-chambers 23, into which oil may be introduced through apertures 24 in the top of the journal-box, there being openings 25 in the lower portion of said blocks for permitting lubricating material to pass therefrom in order to lubricate the shaft 19, the lubricant dropping from said shaft down onto the shaft 17, and from thence to the axle, in order to thoroughly lubricate all 60 the parts.

26 represents U-shaped flanges on the outer plate 27 of the journal-boxes and on the back plate of the same, said flanges serving to some extent to keep the shaft 17 in proper alignment, said plate 27 being also provided with flanges 28, which pass to either side of the oil-chambers 23 in order to render said face-plate more solid in its connection with the journal-box, the face-plate 27 being provided 65 with dust-tight flanges 29 on its sides and top to prevent dust and foreign substances from entering into the journal-box, said flanges being provided with holes 30, through which they may be secured by means of bolts to the 75 body of the box. 31 represents peep-holes in said plate for examining the axle and rollers, said openings being closed normally by means of plates 32 33, pivoted to face-plate 27.

The lower section 12 of the journal-box, 80 which is secured to the main section, as heretofore described, is provided with two rollers 34, which bear against the under side of the axle 15, said rollers having shafts 35, having suitable bearings in said section 12, the purpose of said rollers being to prevent friction caused by side-thrusts of the lower portion of the journal-box.

In the modification as shown in Fig. VI the rollers 34 are dispensed with and in their place is inserted bushings 36, having ears 37, by which they are secured to the journal-box by passing through a section of the same and having wedges inserted in the openings 38 in the same. In the section 12 are chambers 39, 90 in which the rollers 34 rotate, said chambers being for the reception of oil or lubricant, and as the rollers rotate with the axle 15 the lubri-

cant is thrown up onto the same, it thus being while in operation automatically lubricated.

40 represents a dust-cap surrounding a portion of the axle at the inner side of the box to 5 prevent dust or other foreign substances from entering said boxing.

I claim as my invention—

1. The combination of the boxing 11, having blocks 20 inclosed therein, roller 18, having 10 a shaft 19, on which said blocks rest, rollers 16, having a shaft 17, on which said roller 18 rests, and an axle on which the rollers 16 rest for the purpose of supporting a journal-box, substantially as set forth.

15 2. The combination of the box 11, having rollers 18 16, shaft 19 of the roller 18, blocks for supporting said journal-box, said blocks resting on shaft 19 of the roller 18 and having oil-chambers, openings into and from said 20 oil-chambers, rollers 16, having a shaft 17, on which the roller 18 rests, an axle 15, a movable section 12, and rollers 34, journaled in said section, substantially as set forth, and for the purpose described.

25 3. The combination of a truck-frame 3, supporting-rod 4, tie-rods 7 and 9, journal-boxes

5, to which said tie-rods and supporting-rods are connected, rollers 18 and 16 within said box for supporting the same on an axle, and a face-plate 27, said face-plate and box having U-shaped flanges 26 for guiding the shaft 17 of the rollers 16, substantially as set forth, and for the purpose described.

4. The combination of the box 11, having rollers 18 16 therein for supporting the same, 35 shaft 17, connected with rollers 16, shaft 19 of roller 18, blocks 20, resting on said shaft 19 and supporting said box, and a face-plate 27, having dust-flanges 29 and guiding-flange 28, substantially as described, and for the pur- 40 pose set forth.

5. The combination of a journal-box, suitable rollers therein for supporting said box, and a face-plate 27, removably secured to said journal-box, said face-plate having openings 45 31 for the inspection of the interior of said box, substantially as-and for the purpose set forth.

CLARENCE A. BURTON.
